UNITED STATES PATENT OFFICE.

BENJAMIN C. ODELL, OF KINGSTON, NEW YORK.

CONVERTIBLE NURSERY-CHAIR.

SPECIFICATION forming part of Letters Patent No. 247,847, dated October 4, 1881.

Application filed October 15, 1880. (Model.)

To all whom it may concern:

Be it known that I, BENJAMIN C. ODELL, of Kingston, in the county of Ulster and State of New York, have invented a new and Improved 5 Convertible Chair; and I do hereby declare that the following is a full, clear, and exact description of the same, reference being had to the accompanying drawings, making part of this specification.

10 This invention is in the nature of an improvement in convertible chairs; and the invention consists in a convertible chair constructed with a vertically-adjustable push-handle with wheels fixed to the lower ends of its bars, a hinged foot-rest with rollers secured to the ends of its supporting-bars, pivoted legs hinged to a base which is combined with and carries on its upper surface rockers fixed to the seat of the chair, and an adjustable back-panel, in combination with the push-handle of the chair.

15 In the accompanying sheet of drawings, Figure 1 represents a side view, partly in section, of my invention when used as a high chair; Fig. 2, a front view of same; and Fig. 3, a side 20 view, partly in section, when the device is used as a carriage.

25 Similar letters of reference indicate like parts in the several figures.

30 A represents the base of my chair, and it may be of any desirable shape and size. At the rear of this base are formed two slots, *a*, with pins *b* inserted through the sides of the same; also, to this base, and near its rear side, are hinged the front legs, *B*, of the chair. To these 35 front legs, near their upper ends, are pivoted rear legs, *C*. To the front side of the base *A* are hinged the supporting-bars *D* of the foot-rest *c*. Near the outer extremities of these bars are fixed one or more rollers, *d*. Passing through 40 the slots *a* in the base *A* are the bars *E*, which, with the stretchers *e*, constitute the push-handle of the contrivance. These bars are fitted to have a vertical sliding movement within the slots *a*, and to the lower ends of these bars are 45 secured, by means of an axle or otherwise, wheels *F*.

Upon the upper surface of the base *A* are placed and secured rockers *G*, fixed to the seat *f* of the chair. These rockers may be held to 50 the base by coil-springs *g*, which will also assist the rocking movement of the chair; or they

may have any other suitable affixing device secured to them for that purpose.

To the back posts, *H*, of the chair, and between them, is pivoted at its lower side an adjustable panel, *J*. This panel, when between the back posts or vertical, forms a rest for the back of the occupant, but when it is swung back so that its upper side is supported by the bars *E* of the push-handle it forms an inclined 55 continuation of the seat of the chair, transforming the chair into a couch.

My chair being constructed substantially as above described, it is operated as follows: When the chair is upright and in position to 60 be used as a high chair, it is supported by the lower ends of the pivoted legs *B* and *C*, as are the ordinary chairs having crossed and hinged legs. When in this upright or highest position the legs are secured to the base *A* by any 65 suitable catch, as at *h*, Fig. 1, and the bars *E* of the push-handle are then vertical, or nearly vertical, with the wheels *F* raised from contact with the floor. This raised and vertical position of the push-handle is maintained by notches 70 formed in the edges of the bars, which notches interlock with the pins *b* in the sides of the slots *a*, or by means of the stretcher *e*, resting on the base *A*; and also, when the chair is in this raised or highest position, the supporting-bars *D* of the foot-rest *c*, together with the roller or rollers secured thereto, are inclined 75 somewhat from the vertical between the front legs, *B*, in which position they may be held in any suitable manner.

80 To lower the chair that it may form a trundle or carriage, the catch *h* is detached, the front and rear legs, *B* and *C*, spread outward, front and rear, and the wheels *F* at the ends of the bars *E* of the push-handle are brought in contact with the floor, forcing the bars of the push-handle to assume an inclined position 85 back of the chair, with the wheels *F* centrally beneath the legs of the chair and chair-seat, in which position the wheels and push-handle are 90 retained by the notch *l* in the bars *E* of the push-handle, these notches interlocking with the pins *b* through the sides of the slots *a*. When the legs *B* and *C* are spread outward to transform the chair into a carriage the supporting-bars *D* of the foot-rest *c*, with its wheel 95 or wheels affixed, are inclined outward from the 100

front of the chair or its base A, in which inclined position they are retained by any suitable device, and when these bars are in this inclined position the wheel or wheels d and the 5 wheels F are in contact with the floor, the legs B and C being raised from it, offering no obstruction to the free trundling or wheeling of the chair. The legs of the chair are held in this raised position by any suitable catch, as at m. 10 When the chair is in its lowest position, forming a carriage, the adjustable panel J can, if desired, be turned backward from between the back posts of the chair, with its upper side resting against and supported by the bars E of the 15 push-handle, and its lower side secured to the back post by pivots which admit of its turning. When in this position the chair is transformed into a couch, upon which the occupant may recline. When the chair is in its elevated or high- 20 est position this adjustable panel is wholly between and parallel with the back posts, and affords the ordinary back-support. Whether the chair be in its lowest position, as a carriage, or resting upon its legs in its elevated position, 25 as a high chair, is immaterial to the working or rocking of the chair upon the base A, it being equally useful as a rocking-chair in either position.

From the foregoing it will be seen that my 30 chair combines together in a simple and useful manner a high chair, carriage, rocking-chair, and couch, and, if you please, cradle, since the chair may be rocked on its base when

the panel J is thrown out in the manner before described.

To the arms of the chair is attached, in any 35 desirable manner, the play-table and guard L.

Having thus described my invention, what I claim as new, and desire to secure by Letters Patent, is—

1. The combination, in a convertible chair, of the base A, having slots a and pins b, bars E, having notches l and carrying the wheels F, pivoted legs B C, and the foot-rest-supporting bars D, hinged to the base A and carrying 45 the wheel d, as and for the purpose described.

2. In a convertible chair, an adjustable back panel pivoted to the back posts of the chair, in combination with the cross-bar of an adjustable push-handle, substantially as and for the 50 purpose described.

3. In a convertible chair, the combination, with hinged and pivoted legs to support the chair in its highest position, of the hinged foot-rest-supporting bars D, having wheel d and 55 the push-handle bars E, having wheels F, as and for the purpose described.

4. In a convertible chair, the combination of a base, rockers placed thereon, an adjustable panel, and an adjustable push-handle, where- 60 by the chair may be transformed into a cradle, substantially as described.

BENJAMIN C. ODELL.
